UNITED STATES PATENT OFFICE.

ALEXANDRE M. GREAN, OF NEW YORK, N. Y.

GARMENT-SUPPORTER.

1,230,889.

Specification of Letters Patent. Patented June 26, 1917.

Application filed December 17, 1913. Serial No. 807,265.

To all whom it may concern:

Be it known that I, ALEXANDRE M. GREAN, a citizen of the United States, residing at New York, in the county of New York and State of New York, have invented new and useful Improvements in Garment-Supporters, of which the following is a specification.

The present invention relates to garment supporting means, and more particularly to means for supporting collars.

One of the important features of this invention is the employment of a plurality of supporting standards and the construction thereof. These are formed of non-metallic filaments, preferably of animal substance, and in the preferred embodiment, comprise the hardened attenuated substance obtained from certain glands of silk worms.

One manner of producing the material is to kill the fully developed larvæ prior to the time they spin their cocoons and to withdraw the viscous fluid found in the silk glands thereof. This fluid is immediately drawn out to the condition of a fine uniform filament, which is suitably supported and dried, preferably in the presence of sunlight. The resultant product is a very light, strong and tenacious filament, which at the same time is elastically flexible or resilient.

Pieces of this filament are then moistened and preferably doubled to form the supporting standards. The doubled portions, forming each standard, are either bound or twisted together and immersed in a bath of liquid celluloid, rubber, lacquer or the like, which binds the sections of the standard together, produces a stiffening and reinforcing coating, and yet does not affect materially the resilient qualities of the structure.

Two embodiments of the invention are illustrated in the accompanying drawings, wherein:—

Figure 1 is a perspective view of a collar supporter, constructed in accordance with the present invention.

Fig. 2 is a detail view on an enlarged scale of one of the standards.

Fig. 3 is a cross sectional view on an enlarged scale on the line 3—3 of Fig. 1.

Fig. 4 is a horizontal sectional view through one of the standards, the same being shown on an enlarged scale and being on the line 4—4 of Fig. 2.

Fig. 5 is a detail perspective view showing a slightly modified form of standard.

Fig. 6 is a sectional view of the same.

Similar reference numerals designate corresponding parts in all the figures of the drawings.

In the embodiment illustrated, a plurality of standards 7 are employed, and each standard, as above explained, is composed of a doubled strand of the hardened attenuated contents of the silk ducts of silk worms. The doubled arms or strands 8 thus produce a loop 9 at the upper end of the standard, and the terminals of said strand are oppositely outturned, as illustrated at 10. The strands are bound together by silk or other thread, or the like, as shown at 11, and 70 they are then dipped in a bath of liquid celluloid, rubber, lacquer, or the like, producing a coating 12 which binds the strands together, completely inclosing the same and also inclosing the binders 11. This material 75 constitutes a stiffening, binding, waterproof and protective coating for the strands.

These standards are then secured together, preferably by the following means: A core strip 13 is doubled over the terminals 10, 80 and portions of the standards including the said terminals, are secured to this core strip by waterproof cement, or the like, indicated at 14. Over the core strip is doubled a binding or facing strip 15, the margins 16 85 of which are doubled inward and the whole is secured together by a line of stitching, as 17.

It will be evident that a long body of this material may be constructed and suitable lengths cut off as wanted for use. Or the same may be manufactured in predetermined lengths, comprising complete collar supports. It will also be evident that a single standard with a section of the binding material may be utilized.

In the form illustrated in Figs. 5 and 6, the structure is substantially the same, except that the strands 8^a are twisted together, instead of being bound. These strands, however, are doubled to produce at one end the eye and at their other end are provided with the offset terminals 10^a which are cemented within a core strip 11^a, that in turn is inclosed in a binding or facing strip 12^a, the 100 whole being sewed, as shown at 13^a. In this case also the strands are inclosed in a coating 14^a.

The material employed in the manufacture of this collar supporter is of importance for the following reasons. In the first place it is entirely rust-proof, it can be

produced in different lengths, and of various diameters to suit different requirements of use. It may be bent and twisted and made to retain any form desired for use. At the 5 same time, it is light in weight and will so blend with the color of the collar that it is not noticeable.

From the foregoing, it is thought that the construction, operation and many advantages of the herein described invention 10 will be apparent to those skilled in the art, without further description, and it will be understood that various changes in the size, shape, proportion and minor details of construction may be resorted to without departing from the spirit or sacrificing any of the 15 advantages of the invention.

Having thus fully described my invention, what I claim as new and desire to secure by 20 Letters Patent, is—

1. A garment supporter comprising a resilient standard formed of the hardened attenuated contents of the silk ducts of silk worms.

2. A garment supporter comprising a resilient standard formed of the hardened attenuated contents of the silk ducts of silk worms, and a stiffening and binding coating covering said material and permitting the 30 elastic action thereof.

3. A garment supporter comprising a plurality of separate resilient standards having independent offset bases extending outwardly from and transversely of the standards, and a binding strip securing the bases together at one end of each, leaving the opposite ends free, said offset bases being disposed longitudinally of the strip.

4. A garment supporter comprising a plurality of separate resilient standards, each comprising a doubled strand and having oppositely offset terminals that are in substantial alinement but independent of one another, and a binding strip inclosing the 45 offset terminals of the various standards and disposed longitudinally thereof, said strip securing the same together.

5. A garment supporter comprising a plurality of standards, a core strip cemented 50 thereto and connecting the standards, and

a binding strip inclosing the core strip and the ends of the standards cemented to said core strip.

6. A garment supporter comprising a plurality of resilient standards, each composed 55 of a doubled strand formed of the hardened attenuated contents of the silk ducts of silk worms, the terminal portions being oppositely offset, a core strip inclosing and connecting the offset ends and cemented thereto, 60 and a binding strip inclosing the core strip and sewed to the same.

7. A garment supporter composed of a filament of the hardened attenuated contents 65 of the silk ducts of silk worms, and comprising a standard formed by the doubling of such filament upon itself.

8. An individual collar supporter, comprising a single standard formed from a length of filamentary material bent upon itself to 70 produce a plurality of strands, said strands being twisted together throughout the length of the standard to form a single shank having means at both ends, whereby it can be attached to a collar, at least one of 75 said means being an eye formed by the bending of the filament, and the ends of said filament being so disposed with respect to the attaching means that they will be protected thereby from pricking the neck of the 80 wearer.

9. A collar supporter comprising a standard formed from a single length of pliable filamentary material bent to form a plurality of strands that lie side by side and 85 are twisted together throughout the length of the standard, said standard having a terminal consisting of a loop or eye formed in bending the material, and a substantially waterproof seamless coating surrounding the standard at the eye and acting as a 90 binder for the strands of said standard while permitting the flexing of the standard.

In testimony whereof I have hereunto set my hand in presence of two subscribing witnesses.

ALEXANDRE M. GREAN.
